UNITED STATES PATENT OFFICE.

JOHN F. ORR, OF CINCINNATI, OHIO, ASSIGNOR TO THE CINCINNATI COFFIN COMPANY, OF CINCINNATI, OHIO, A CORPORATION OF OHIO.

DESIGN FOR A LINING FOR BURIAL-CASKET LIDS.

46,413.

Specification for Design.

Patented Sept. 15, 1914.

Application filed July 31, 1911. Serial No. 641,642. Term of patent 7 years.

To all whom it may concern:

Be it known that I, JOHN F. ORR, a citizen of the United States of America, and a resident of Cincinnati, county of Hamilton, and State of Ohio, have invented a new, original, and ornamental Design for Linings for Burial-Casket Lids, of which the following is a specification, reference being had to the accompanying drawing forming a part thereof.

The figure is an elevation of the inner face of a lid of a burial casket, showing my new design for the lining.

The inner face of the lid has a covering of silken cloth, which is formed into tufts, as

shown in the drawing, but beneath the tufts no backing nor stuffing material is placed, so that each tuft will present a soft or fleecy appearance, such as is produced by light summer clouds or ocean foam. The shade lines in the drawing are intended to represent this effect.

I claim:

The ornamental design for a lining for burial casket lids, as shown and described.

JOHN F. ORR.

Witnesses:

WALTER F. MURRAY,
W. THORNTON BOGERT.
